UNITED STATES PATENT OFFICE

MCCLELLAND BARCLAY, OF LOS ANGELES, CALIFORNIA

DESIGN FOR A COMBINED RADIATOR, HOOD, FENDERS, AND BUMPER FOR VEHICLES

Application filed June 20, 1932. Serial No. 44,132. Term of patent 7 years.

To all whom it may concern:

I, McCLELLAND BARCLAY, a citizen of the United States, residing at Los Angeles, in the county of Los Angeles and State of California, have invented a new, original, and ornamental Design for a Combined Radiator, Hood, Fenders, and Bumper for Vehicles, of which the following is a specification, reference being had to the accompanying drawing, forming a part thereof.

Fig. 1 is a front elevation of the combined radiator, hood, fenders, and bumper for vehicles of the design, and Fig. 2 is a perspective view thereof.

I claim:

The ornamental design for a combined radiator, hood, fenders, and bumper for vehicles, as shown.

McCLELLAND BARCLAY.
